STOCKING

Otto F. Smetana, Concord, N. C.

Application July 9, 1941, Serial No. 401,559

11 Claims. (Cl. 66—182)

This invention relates to stockings, and it has reference more particularly to fashioned stockings formed from blanks which are knitted flat, complete with leg and foot, in a continuous operation on one knitting machine, and which are characterized by having their heel cheeks shaped by widening and narrowing, that is to say, by addition of extra end loops occasionally during the knitting of the upper portions of the heel cheeks, and by progressive narrowing or occasional inward transfer of end loops during the knitting of the bottoms of said cheeks.

Many of the stockings of the kind referred to, now being marketed, have the tendency to become displaced or twisted at the ankle of the wearer as a consequence of the shifting of the heel incident to movement of the leg and foot in walking. This difficulty is usually due to incorrect proportion of the heel, and improper distribution of strains in the fabric in the heel region.

The main object of my invention is to overcome the above drawback, that is to say, it has for its chief aim to provide a continuously knitted stocking whereof the foot in the region of the heel is accurately configured and proportioned to properly fit the wearer's foot, and wherein the strains are so distributed incident to walking, that up and down or lateral displacement of the heel cannot possibly take place to distort or twist the ankle of the stocking.

How the foregoing and other important objects and advantages may be readily realized in practice will appear from the following detailed description when taken in connection with the attached drawings, wherein—

Fig. 1 is a view in side elevation of the foot of a continuously knitted fashioned stocking conveniently embodying my invention.

Fig. 2 is a similar view showing how the stocking appears on the foot of the wearer.

Fig. 3 is a view of the stocking looking as indicated by the arrows III—III in Fig. 2; and

Fig. 4 is a diagrammatic view showing the flat knitted fashioned blank from which the stocking is formed.

With reference first to Fig. 4 of the drawings, it may be assumed that the stocking blank there shown is formed in the usual way down to the ankle portion which is designated A. The blank may be knitted from either a single main or body yarn, or it may be made as a ringless structure by employing three main or body yarns of the same gauge or count in alternation in a manner well known in the art. After the line 10—10 is reached, the fabric is progressively widened by 55

addition of end loops down to a line 11—11 to shape the upper portions of the heel cheeks H. With this accomplished, a short length of uniform width fabric is produced down to a line 12—12, whereupon the fabric is narrowed at a relatively moderate rate down to a line 13—13, the latter two steps resulting in the formation of the intermediate portions of the heel cheeks H. From then on down to a line 14—14a, 14b, 14c, the fabric is further narrowed but more rapidly than before at a rate comparable to the rate of the widening in the upper heel portions, to form the bottom portions of the heel cheeks H, said cheeks being thus non-symmetrical with respect to their transverse axes which are represented by the line 13—13. Continuing from the line 14—14a, 14b, 14c narrowing is again resorted to down to a line 15—15a, 15b, 15c, but at a more moderate rate than in the bottom portions of the heel cheeks; whereupon the instep portion I of the foot is knitted in continuation as a parallel edged web down to a line 16—16a, 16b, 16c. The toe T of the stocking is then formed by resorting to narrowing down to a line 17—17a, 17b, 17c. In practice, the widening from the line 10—10 and 11—11 is effected by adding two end loops to each edge of the fabric in every fourth course of the knitting and by making approximately twenty-three step-outs; while between the lines 11—11 and 12—12 approximately twelve courses are knitted. The narrowing between the lines 12—12 and 13—13 is effected by inwardly transferring two or three edge loops by the distance of one needle every seventh course of the knitting and by making approximately two narrowings. In the fabric between the lines 13—13 and 14—14a, 14b, 14c, approximately nineteen narrowings are made with two plain courses intervening in each instance, and by inward transfer, as before, of two or three end loops the distance of one needle each time, the lines of narrowing marks in each instance extending closely adjacent the corresponding segments of the selvages so as to be incorporated in the seam when the stocking is subsequently sewed up in the usual manner. In the fabric between the lines 14—14a, 14b, 14c and 15—15a, 15b, 15c there are approximately nine narrowings with three plain courses intervening each time. The latter narrowings are formed by inward transfer of approximately twenty end loops inwardly the distance each time of one needle with the result that the lines of narrowing marks 14a—15a and 14b—15b are well inward of the corresponding segments 14—15 and 14c—15c of the selvages and therefore out of line with the

narrowing marks along the segments 13—14 and 13—14c. If found desirable, a half dozen or so courses of uniform width may be interposed between the contiguous ends of the narrowing 13—14, 13—14c and 14—15, 14c—15c.

By the use of additional or splicing yarns, the foot portion of the blank may be reinforced along opposite sides in the region of the heel and instep from wales inward of the ankle and instep selvages and the splicing so controlled as to produce the well known "cradle" effect with upward extensions of the reinforcements to serve as high heel areas above the line 10—10. In accordance with my invention, the heel cheeks are additionally reinforced outward from the wales corresponding to the ankle selvages, as indicated by the heavy line wale shading, by the use of still other splicing yarns, and during the knitting of these additionally reinforced areas, the loops constituting the portions of the fabric courses within said areas are graduated, that is to say, they increase gradually in size from the normal beginning with wales 10—14 and 10—14c in line with the ankle selvages outward to the heel selvages. This latter step is advantageous in that it assists in giving the heels a more rounded configuration with avoidance of puckering at the selvages.

It will be seen that by widening and narrowing at varying rates as above explained in knitting the heel cheeks, that a substantially round and hence more perfectly fitting heel results in the completed seamed stocking, and that by resorting to the additional narrowing between the lines 14—14a, 14b, 14c and 15—15a, 15b, 15c, smoother emergence is had between the heel and the instep I. These important characteristics of my improved stocking are clearly brought out in Figs. 1, 2 and 3.

The offsetting of the narrowing mark lines 14a—15a and 14b—15b relative to the narrowing mark lines 12—13—14 and 12—13—14c results in a break between these lines at the region of emergence of the heel bottom with the sole. Accordingly the heel cannot be displaced either up or down or laterally by wale-wise pull from the toe, while at the same time the fabric is left amply elastic for capacity to expand and contract transversely between the front of the ankle and the heel bottom. In addition to enhancing the wearing qualities of the stocking, the double splicing in the heel cheek areas projecting beyond the line of the ankle selvages restricts the elasticity of the heel fabric to a certain extent. As a consequence, the heel is stiffened against distortion, with the further assurance that it will more effectively resist displacement. The additional reinforcement has the further effect of strengthening the wales between the points 10—14 and 10—14c which are in line with the ankle selvages, to the end that the heel cannot be distorted or displaced by upward pull from the leg.

It is of course to be understood that the number of widenings and narrowings employed and the degrees of lateral stepping in fashioning the heel cheeks may, within the scope of the appended claims, vary considerably from those herein given by way of example, according to size differences in the stockings or in order to meet special requirements of practice.

Having thus described my invention, I claim:

1. A fashioned stocking formed from a flat-knitted selvaged blank with laterally-projecting heel cheeks which are non-symmetrical with respect to their transverse axes, the upper and lower portions of said cheeks having side edges

which slope outwardly and inwardly respectively at substantially-corresponding angles in respect to the fabric wales, and the intermediate portions of said cheeks having side edges which slope in the same general direction as the side edges of said lower portions but at a lesser angle to the fabric wales.

2. A stocking according to claim 1, in which the intermediate portion of each heel cheek is defined in part by a selvage segment which extends parallel to the fabric wales.

3. A stocking according to claim 1, having an instep portion with parallel side edges, and a zone between the lower heel portions and the instep portion defined by selvage segments which slope inwardly at a lesser angle to the fabric wales than those of said lower heel portions.

4. A fashioned stocking formed from a flat-knitted selvaged blank having laterally-projecting heel cheeks with upper widened portions and narrowed lower portions, in which the fabric at the region of the heel cheeks is reinforced to wales inward of the ankle selvages, and in which the heel cheeks are additionally reinforced outward from the wales corresponding to the ankle selvages.

5. A fashioned stocking formed from a flat-knitted selvaged blank having laterally-projecting heel cheeks with upper widened portions and lower narrowed portions, in which the heel cheeks are reinforced outward from wales corresponding to the ankle selvages, and in which the loops in the heel cheeks are graduated in size outwardly from said wales toward the heel cheek selvages.

6. A fashioned stocking formed from a flat-knitted selvaged blank having laterally-projecting heel cheeks with upper widened portions and lower narrowed portions, in which the heel cheeks are reinforced outward from wales corresponding to the ankle selvages, and in which the loops in the heel cheeks increase in size outwardly from said wales toward the heel cheek selvages.

7. A fashioned stocking formed from a flat-knitted selvaged blank having laterally-projecting heel cheeks with widened upper portions and with narrowed lower portions, in which the fabric in the region of the heel cheeks is reinforced to wales inward of the ankle selvages, in which the heel cheeks are additionally reinforced outward from wales corresponding to the ankle selvages, and in which the loops in the additionally-reinforced areas of the heel cheeks are graduated in size outward from the last mentioned wales toward the heel cheek selvages.

8. A fashioned stocking formed from a flat-knitted selvaged blank having laterally-projecting heel cheeks with upper widened portions and lower narrowed portions, in which the fabric in the region of the heel cheeks is reinforced to wales inward of the ankle selvages, in which the heel cheeks are additionally reinforced outward from wales corresponding to the ankle selvages, and in which the loops in the additionally-reinforced areas of the heel cheeks gradually increase in size outwardly toward the heel cheek selvages.

9. A fashioned stocking formed from a flat-knitted blank with laterally-projecting widened and narrowed heel cheeks having their upper and lower portions widened and narrowed respectively at substantially the same rate and their intermediate portions narrowed at a lesser rate than their bottom portions, said cheeks being reinforced outwardly from wales corresponding to the ankle selvages, and the loops in the reinforced areas of

the heel cheeks being graduated in size outwardly toward the heel cheek selvages.

10. A fashioned stocking formed from a flat-knitted selvaged blank having laterally-projecting heel cheeks with upper widened portions and with lower narrowed portions which are characterized by lines of fashioning marks parallel to the selvage segments defining said lower heel portions, a parallel-edged instep portion, and a narrowed zone between the lower heel portions and 10 the instep portion characterized by lines of

fashioning marks which are farther inward from the selvages than the lines of narrowing marks in said lower heel portions.

11. A fashioned stocking according to claim 10, in which the heel cheeks are reinforced outward from wales corresponding to the ankle selvages of the blank, and in which the loops of the heel cheeks are graduated in size outwardly from said wales toward the heel cheek selvages.

OTTO F. SMETANA.
